UNITED STATES PATENT OFFICE.

RICHARD J. SPENCER, OF CHATTANOOGA, TENNESSEE.

BRONZING MACHINE.

Application filed April 15, 1922. Serial No. 553,189.

To all whom it may concern:

Be it known that I, RICHARD J. SPENCER, a citizen of the United States, residing at Chattanooga, in the county of Hamilton and State of Tennessee, have invented new and useful Improvements in Bronzing Machines, of which the following is a specification.

This invention relates to an attachment for printing presses and has for its object the provision of a novel device designed to be mounted upon a cylinder printing press for the purpose of applying bronze powder or powder of any kind to the printed sheets while they are still wet, the device having the great advantage of eliminating the usual manual labor involved in this operation and consequently being a great time saver.

An important and more specific object is the provision of a device of this character designed for association with a cylinder printing press and including a housing into which is fed the bronzing powder and within which operates a distributing roller which is positively driven by one of the gears of the press mechanism, this roller operating to apply the powder to the wet printed sheets immediately upon their leaving the type.

Another object is the provision of a device of this character in which ample means is provided for effecting whatever adjustment may be necessary to take up wear between the various intermeshing gears so as to prevent back lash.

An additional object is the provision of a device of this character which will be simple and inexpensive in manufacture, and in installation, highly efficient in use, positive in service, and a general improvement in the art.

With the above and other objects and advantages in view, the invention consists in the details of construction to be herein-after more fully described and claimed, and illustrated in the accompanying drawings, in which:

Figure 1 is a side elevation of a portion of a cylinder printing press showing my device applied thereto.

Figure 2 is a top plan view.

Figure 3 is a cross sectional view through my device.

Figure 4 is a detail horizontal sectional view through one side of the frame showing the adjusting means for the structure.

Figure 5 is a detail longitudinal sectional view taken through the housing and distributing roller.

Figure 6 is a detail perspective view of the slide.

Figure 7 is a detail section showing the means for regulating the outlet of the powder.

Referring more particularly to the drawings, the letter A designates a portion of the frame of a cylinder printing press, B designates the bed thereof, and C designates one of the driving gears. As the present invention is not concerned with the ordinary printing mechanism, certain parts thereof are illustrated more or less diagrammatically but not in detail.

In carrying out my invention I provide a pair of frame members 10 which are bolted upon opposite sides of the frame A at some convenient location and which terminate in horizontally extending arms 11 formed with elongated rectangular openings 12 within which are slidably disposed bearing members 13 through which is journaled a shaft 14 carrying a roller which consists of a wooden core 15 covered with many layers of cloth 16 of felt or other fabric. Threaded through the webs at opposite ends of the opening 12 are set screws 17 which engage the bearing member 13 and which are for the purpose of adjusting the position of the bearing members and consequently the position of the cloth covered roller.

The numeral 18 designates broadly a housing which surrounds the cloth covered roller and which is formed or provided with arms 19 which are adjustably connected with the frame members 10 by means of bolts 20 which pass through elongated slots 21 in the frame members. At one portion in its periphery this housing 18 is interrupted or cut away as shown at 22 for a purpose to be described. At another point in its periphery the housing is formed with an enlarged hollow portion 23 which is designed as a reservoir for containing the bronzing powder to be used upon the printed sheet. The top of this reservoir and the top of the housing are closed by covers 24 and 25 respectively. These covers are united by

the same hinges 26 and are provided at their ends with fastening members 27 which may be operated to hold the covers closed or to permit them to be opened. These covers 5 are also provided with any suitable handles or finger grips by means of which they may be more conveniently lifted though such are not an essential feature.

The wall of the housing between the reservoir 10 and the inner periphery which is adjacent the cloth covered roller is formed with a plurality of perforations 28 which are for the purpose of allowing the bronzing powder within the hollow compartment to 15 pass down onto the cloth covered roller. A very important feature is the provision of a longitudinally slidable plate 29 which is formed with perforations 30 adapted to register with the perforations 28 and which is 20 mounted within spaced guides 31 on the housing. One end of this slidable plate is provided with a handle lug 32 by means of which it may be moved back and forth to cover or uncover to a greater or less extent 25 the perforations 28 in the housing. In this way it will be seen that the feed of the powder may be regulated at will to meet any and all conditions which may arise in the operation of the device.

Secured upon the shaft 14 at one end of 30 the roller is a pinion 33 meshing with an intermediate pinion 34 journaled at 35 upon the frame member 10 and meshing, in turn, with the gear C of the printing press mechanism.

Assuming that the device has been constructed and assembled as above described, in the operation it will be seen that as the printed sheets pass from the cylinder of the printing press they will pass over the cut 40 away portion 22 of the housing and will brush lightly against the cloth covering 16 of the roller. Owing to the fact that this roller is constantly rotated by means of the gear C and owing to the provision of the 45 perforated slide plate controlled outlet in the portion of the housing which separates the powder container from the portion within which the roller rotates, the external surface of the cloth of the roller will be constantly covered with the bronzing powder. As the sheets of paper having the ink or 50 sizing thereon still wet pass in a contact with this cloth covered roller, it is apparent that the particles of bronzing powder thereon will adhere to the wet ink or sizing so as to produce the desired effect. It is to be noted that in case of looseness in the intermeshing of the gears, that is in the event of 55 any back-lash or play, the set screws 17 may be adjusted to bring the pinions properly into engagement with each other and with the gear C for insuring the proper action. Owing to the fact that the bolts 20 which 60 hold the housing in position pass through

the elongated slots 21 in the frame members 10, it will be apparent that the housing itself may be adjusted with respect to the cloth covered roller so as to cause the latter to be always central with respect to the 70 housing. In this way it will be seen that ample provision is made for taking care of all variations such as occur in the dimensions of different cylinder presses and also to take up any wear which may occur. 75 Owing to the adjustability of the shaft carrying the cloth covered roller it is apparent that the degree of pressure exerted thereon against the sheets may be regulated so that the cloth covered roller will touch the wet 80 sheets only very lightly so as to avoid any possibility of smearing.

From the foregoing description and a study of the drawings it will be apparent that I have thus provided a simply constructed and consequently inexpensive device which may be manufactured and sold commercially as a separate entity adapted for installation upon or for attachment to already existing printing presses of the cylinder type. It is also to be noted that the device might be built into the presses during their manufacture without involving any very great additional expense. Owing to the provision of the various adjusting means and owing to the general relation and association of the parts, it is apparent that the device will operate very efficiently to produce the proper bronzing effect in an extremely rapid, simple and economical manner, the ordinary manual labor usually involved being entirely eliminated so that a vast amount of time will be saved.

Owing to the simplicity of the construction and the fewness of the parts it is apparent that there is nothing to get out of order and that the device should consequently have a long life and satisfactorily perform all the functions for which it is intended.

While I have shown and described the preferred embodiment of the invention, it is of course to be understood that I reserve the right to make such changes in the form, construction and arrangement of parts as will not depart from the spirit of the invention or the scope of the subjoined claims.

What is claimed is:

1. A bronzing attachment for cylinder presses comprising an elongated casing provided with means for attachment to the frame of a cylinder press, said casing being cylindrical throughout the major portion of its cross sectional configuration but having one upper corner formed rectangular, a 120 cover for said rectangular corner, a curved partition within the casing at said rectangular corner to define a compartment for the storage of bronzing powder, said partition being formed with openings permitting 125 130

outlet of powder from the reservoir compartment into the casing, said casing being formed with a slot, and a driven roller fitting and rotating within the casing and exposed at said slot.

2. A bronzing attachment for cylinder presses comprising an elongated casing provided with means for attachment to the frame of a cylinder press, said casing being cylindrical throughout the major portion of its cross sectional configuration but having one upper corner formed rectangular, a cover for said rectangular corner, a curved partition within the casing at said rectangular corner to define a compartment for the storage of bronzing powder, said partition being formed with openings permitting outlet of powder from the reservoir compartment into the casing, said casing being formed with a slot, and a driven roller fitting and rotating within the casing and exposed at said slot, said partition being formed with guides, and a plate arcuate in cross section slidably mounted upon the partition and formed with holes adapted to register to a greater or less extent with the holes in the partition whereby to regulate the flow of powder.

3. A bronzing attachment for cylinder printing presses comprising a pair of frame members secured upon the frame of the press, a housing carried by said frame members and formed with a reservoir for the storage of bronzing powder, a rotary cloth covered roller operating within said housing and engaged lightly by wet printed sheets leaving the cylinder of the press, a portion of said housing being cut away to expose the roller, means for adjusting the position of the roller toward or from the sheets whereby to regulate the degree of pressure of the con-

tact, and means for adjusting the position of the housing independently of the roller.

4. A bronzing attachment for cylinder printing presses comprising a pair of frame members secured upon the frame of the press, a housing carried by said frame members and formed with a reservoir for the storage of bronzing powder, a rotary cloth covered roller operating within said housing and engaged lightly by wet printed sheets leaving the cylinder of the press, a portion of said housing being cut away to expose the roller, means for adjusting the position of the roller toward or from the sheets whereby to regulate the degree of pressure of the contact, and means for adjusting the housing with respect to the frame members including bolts carried by arms formed on the housing and passing through elongated slots in the frame members.

5. A bronzing attachment for cylinder printing presses comprising a pair of frame members secured upon opposite sides of the cylinder printing press, a cylindrical housing adjustably mounted between said frame members and formed with a compartment for the storage of bronzing powder, said compartment being formed with a filling opening normally closed by a closure cap, a portion of said housing being cut away and a rotary covered roller journaled within said housing, said roller having a shaft, bearing members for said shaft slidably mounted within said members, screws threaded through the frame members and engaging said bearings whereby to vary the position of the roller with respect to the printed sheets passing from the cylinder of the press.

In testimony whereof I affix my signature.
RICHARD J. SPENCER.
